UNITED STATES PATENT OFFICE.

LAURENT G. G. DIBBETS, OF THE HAGUE, NETHERLANDS.

ROLLER.

1,128,113.

Specification of Letters Patent.

Patented Feb. 9, 1915.

Application filed July 18, 1914. Serial No. 851,725.

To all whom it may concern:

Be it known that I, LAURENT G. G. DIBBETS, a subject of the Queen of the Netherlands, and a resident of The Hague, Kingdom of the Netherlands, have invented a new and Improved Roller, of which the following is a full, clear, and exact description.

My invention relates to improvements on the rollers used in the Krajewski crusher, which is utilized for crushing and cutting sugarcane before the same enters the ordinary three-roller mill.

The Krajewski crusher is at the present time the most important and successful accessory designed to increase the efficiency and output of any form of cane-grinding plant to which it may be applied. This contrivance acts both as a crusher and as a preparer and equalizer of the feed of the cane as it enters the mill, and is now very generally used in connection with a train of multiple mills. The essential features of the contrivance are two solid, cast-steel rollers about twenty-six inches in diameter and seventy-two inches in length, each provided with pointed zigzag corrugations extending longitudinally of each roller. The corrugations on each of this pair of rollers are arranged to mesh but not to touch when in motion. The rollers are kept at the minimum distance apart by properly constructed blocks, and the degree of their separation is controlled by powerful springs or by suitable hydraulic appliances. The efficiency of said rollers decreases materially as soon as the edges of the zigzag teeth on the rollers become blunt. The surface, due to wear, becomes highly polished so that the teeth fail to grip and hold the cane and do not draw the cane between the rollers for crushing, as intended. This failure of the rollers to grip and carry the cane tends to an accumulation or jam of the cane in front of the rollers. This necessitates the breaking up of the jam by forcing the cane between the rollers with poles or bars, which requires extra help and, therefore, more expense and delay.

To obviate the described defects of the rollers, and to make the operation continuous, automatic and efficient, I have devised a roller which has notches in the teeth thereof and which is illustrated in the accompanying drawings forming a part of the specification, in which similar characters of reference

indicate corresponding parts in both views 55 and wherein—

Figure 1 is an elevation of a roller embodying my invention; and Fig. 2 is a cross section on line 2—2, Fig. 1.

Referring to the drawings, 3 represents a 60 roller the pointed zigzag corrugations 4 of which form sharp-edged teeth, and, as can be seen from the drawing, appear to be formed of a longitudinal series of connected V's, each branch of a V being provided with 65 a notch 5, the effective surface b c of which is substantially radial. The curved portion a b of the notch forms the retaining or gripping part, while the surface b c is the tearing side. The notches of each of said zig- 70 zag-shaped teeth are substantially in alignment and parallel to the axis of the roller. The sharp edges of these cut-outs or notches 5 of the teeth 4 are adapted to grip the cane and thus prevent its slipping as the same is 75 engaged between the rollers; they also help to tear and crush the cane. As shown in Fig. 1, the notches converge or diverge from the line joining the apex of the V and thereby they are adapted to cover a maximum 80 surface, i. e., the area of their action is increased by disposing them as shown. These notches 5 may be recut at the beginning of each grinding season, or at any other desired time, to keep the tearing and gripping edges 85 sharp, that is, effective during the operation. The sharpening is done by simply increasing the width of the notch; particularly the surface b c is attended to.

It will be observed that the tearing and 90 gripping edges formed by the notches can be maintained efficient at very little expense and loss of time, thus increasing the efficiency of the crusher and rendering the same automatic by obviating the jam which 95 takes place in front of the roller when the sharp edges of the teeth 4 become polished.

It is self-evident that existing rollers can be transformed into rollers embodying my invention by cutting out in the edges of the 100 teeth 4 a volume a b c in each branch of the V forming a tooth, thus transforming an ordinary roller into a roller as described. It may be further noted that in lieu of providing the notches 5 diverging or converging with reference to the line joining the apex of the teeth they may be made parallel thereto or staggered successively as the prac- 105

tice may require. In a crushing mill both rollers may be provided with notches 5 in the sharp edges forming the teeth, but preferably the driving roller only is so provided with notches.

Having thus described my invention, I claim as new and desire to secure by Letters Patent:

1. A roller of the class described having sharp-edged, zigzag teeth longitudinal thereof, said sharp edges having notches in said edges.
2. A roller of the class described having sharp-edged, zigzag teeth longitudinal thereof, said edges having notches in each of the branches of the zigzag teeth.
3. A roller of the class described having sharp-edged, zigzag teeth longitudinal thereof, said edges having notches in each of the branches of the zigzag teeth, said notches in each of the teeth being in alinement and parallel to the axis of the roller.
4. A roller of the class described having sharp-edged, zigzag teeth longitudinal thereof, said edges having notches in each of the branches of the zigzag teeth, each

of said notches having one surface thereof substantially radial.

5. A roller of the class described having sharp-edged, zigzag teeth longitudinal thereof, the edges of each of said teeth forming a series of V's, each branch of each V having a notch.

6. A roller of the class described having sharp-edged teeth longitudinal thereof, the edges of said teeth forming a series of V's, each branch of each V having a notch, said notches in each of the branches of the alining teeth being in alinement and substantially parallel to the axis of the roller, each of said notches having one surface thereof substantially radial and the other surface connecting the bottom of said other surface with the edge of the tooth.

In testimony whereof I have signed my name to this specification in the presence of two subscribing witnesses.

LAURENT G. G. DIBBETS.
